UNITED STATES PATENT OFFICE.

JAMES McLOUGHLIN, OF RYE, NEW YORK.

ORE-REDUCING FURNACE.

No. 874,527.

Specification of Letters Patent.

Patented Dec. 24, 1907.

Application filed March 21, 1906, Serial No. 307,239. Renewed May 13, 1907. Serial No. 374,352.

To all whom it may concern:

Be it known that I, JAMES McLOUGHLIN, a citizen of the United States, residing at Rye, Westchester county, New York, have 5 invented certain new and useful Improvements in Ore-Reducing Furnaces, of which the following is a specification.

This invention relates to furnaces for reducing ores with the aid of the electric arc, 10 and it has for its object a furnace whereby zinc ores, or ores containing zinc, and especially oxid ores, either natural or prepared primarily by roasting, may be reduced.

The purpose is to provide a furnace where- 15 in the reduction may be carried on continu- ously and with greater economy than is attained by the usual means.

In the accompanying drawings, which 20 illustrate an embodiment of the invention— Figure 1 shows the furnace in elevation, partly broken away above to illustrate the feeding mechanism; and Fig. 2 is a cross- 25 section of the regulable outlet or discharge, taken at line x^2 in Fig. 1, but enlarged. Fig. 3 is a vertical section of that part of the furnace where the arc is situated and the 30 reduction is going on, taken at line x^3 in Fig. 4; and Fig. 4 is a horizontal section at line x^4 in Fig. 3. These views—Figs. 3 and 4—are 35 detail views on a large scale.

The axis of the furnace will be upright, and it may be of any length or height to adapt it to the purpose desired.

1 is the hopper to receive the ore and 35 reagent, and 2 is the body of the furnace, which may be cylindrical and consist of an iron casing lined with refractory material 3. The ore and reagent put in the hopper is forced down gradually by a screw 4, or the 40 like, to the point in the ore-chamber where the reduction is effected. Gravity may in some cases be relied on to effect the feeding down of the ore, but in any case gravity will aid in feeding, as the furnace is herein represented.

Referring especially to the detail views, 45 Figs. 3 and 4, the metal electrodes 5, preferably of copper, are represented as set oppositely in the walls of the furnace. The arc is formed in the mass of ore 2 in the furnace, and the ore thus reduced, the vaporized metal passing off as fumes. To provide for the escape of the fumes there is formed in the refractory wall of the furnace an annular 50 recess 6, which opens downward to the interior of the furnace a little distance above

the electrodes 5. The fumes rising in this recess from the ore escape through apertures 7 in the furnace wall and enter an annular chamber C formed in a casing 8 on the outer 55 wall of the furnace and escape from said chamber into fume-conduits or pipes 9, which convey the fumes to the usual fume-chamber, or condensing chamber, which has not been herein shown as it is well known to those skilled in the art.

The ashes, scoria and the like pass down from the reduction point and escape at the outlet below, which is provided with means for throttling or constricting it so as to prevent the too free ejection of the scoria by the weight of material above. This constricting device may be formed in various ways, but that shown therein will now be described. At the lower part of the furnace-body the 75 metal casing, which is cylindrical above, is reduced to a square at 10, and to this square portion are hinged two sections 11, of metal. These sections are of somewhat U-shape in cross-section and one fits within the other so 80 that their sides overlap, as in Fig. 2. By pressing together the two pendent sections 11, it will be obvious that the outlet will be more or less constricted or reduced in area, and this constriction may be effected by 85 means of a frame or band 16 secured to one section and provided with a nut 12, and a screw 13 in said nut and either bearing on or collared to the other section, as clearly shown in Figs. 1 and 2.

The current comes to the electrodes 5 by 90 wires 14, from any source, and the electrodes may be made hollow and kept cool by water circulating through pipes 15.

It is not absolutely essential that the axis 95 of the furnace shall be vertical, but it is convenient to have it so.

The operation may be conducted as follows when zinc oxide is to be reduced from ores containing it. The oxid ore of zinc, broken 100 fine, is mixed with coal or other carbonaceous fuel proportioned in quantity to the zinc oxide and other metallic oxides in the ore, an excess of carbon being required to maintain the atmosphere of carbon monoxid necessary 105 for the reduction of the zinc to the metallic state. The current is turned on the arc and the feed-screw set in motion to feed down the ore and reagent as fast as reduced. The zinc is vaporized and passes off in fumes, in a 110 known way, together with CO and CO_2 , and the fumes are condensed for the recovery of

the metallic zinc. The other metals, not vaporizable, will be absorbed by the coke, scoria and gangue and pass off at the outlet.

The operation is continuous; and as the other metals than zinc in the ore do not reach the furnace walls, the latter are protected from destruction thereby.

It will be understood that the conduits for the fumes of zinc will be of the usual material, such as porcelain or glass, or be lined with some similar material. Metal conduits, especially iron, are apt to contaminate the zinc.

It will be noted that there are several characteristic features in this furnace, namely: The fumes pass up through the mass of ore and thence out through the hooded fume-apertures; the outlet for the solid products of the reduction is aligned with the chamber 20 of the furnace, and the regulating means at this outlet constricts the latter axially; that is, the outlet when reduced is still axially aligned, or substantially so, with the furnace chamber.

Having thus described my invention, I claim—

1. A furnace for the reduction of zinc-bearing ores, having an elongated furnace body open at both ends, one open end serving for the admission of the ore and the other serving as an outlet for the solid products of the reduction, means for axially constricting the aligned outlet of the furnace, means for feeding the material in the ore-chamber of 35 the furnace from the receiving to the discharging end, and means for producing an electric arc in the ore-chamber, said chamber having in its walls fume-apertures disposed between the reduction point and the charging end of the furnace and extending from the ore-chamber obliquely outward and toward the receiving end of the chamber.

2. A furnace for the continuous reduction of zinc-bearing ores, comprising an elongated, upright furnace-body, having in it an ore-chamber with fume-apertures in its walls, and an aligned outlet at its bottom for the

solid products of the reduction, and means for producing an electric arc to extend transversely across the ore-chamber below the 50 fume apertures, means for axially constricting the outlet at the bottom, and means in the ore-chamber for forcing the ore downward therein.

3. A furnace for the reduction of zinc-bearing ores, having an elongated, upright furnace-body, provided with a recess 6 in its walls and outlets 7 therefrom for the fumes, means below said recess for producing a transverse electric arc in the furnace, and an 60 outlet below for the solid products of the reduction, said outlet being provided with means for constricting it from opposite sides.

4. A furnace for the continuous reduction of ores containing a vaporizable metal, consisting of an elongated furnace-body having fume-outlets in its walls, means for feeding the ore through the furnace, means for producing an electric arc in the furnace for reducing the ore, and means for constricting 70 the outlet of the furnace, said means consisting of the hinged sections 11, and means for pressing them together for reducing the area of the outlet.

5. A furnace for the purpose specified, 75 having an elongated furnace-body disposed with its axis upright and provided with a fume-recess 6 and fume-outlets 7 therefrom, a hopper 1 at the upper end of said body, a screw 4 for feeding the ore downward in a 80 continuous manner, metal electrodes 5, set in the furnace-walls below the fume-recess and means for constricting the open discharge end of the chamber in the furnace so as to regulate the discharge of the scoria, ashes 85 and the like.

In witness whereof I have hereunto signed my name this 19th day of March 1906, in the presence of two subscribing witnesses.

JAMES McLOUGHLIN.
